(57) **CLAIM**

The ornamental design for an electrode tip for resistive welders, as shown and described.

DESCRIPTION

FIG. 1 is a perspective view of the electrode tip for resistive welders showing the tip in an assembled alternate condition of use;

FIG. 2 is an exploded perspective view of the electrode tip for resistive welders of my new design;

FIG. 3 is a top perspective view thereof;

FIG. 4 is a top view thereof;

FIG. 5 is a front view thereof;

FIG. 6 is a left side view thereof;

FIG. 7 is a right side view thereof;

FIG. 8 is a back view thereof; and,

FIG. 9 is a bottom view thereof.
